Primary Examiner — Mark Goodwin(57) **CLAIM**

The ornamental design for a front weight for an agricultural tractor, as shown and described.

DESCRIPTION

FIG. 1 is a top front perspective view of the front weight for an agricultural tractor showing my new design.

FIG. 2 is a bottom rear perspective view thereof.

FIG. 3 is a front view thereof.

FIG. 4 is a rear view thereof.

FIG. 5 is a side view thereof.

FIG. 6 is an opposite side view thereof.

FIG. 7 is a top plan view thereof; and,

FIG. 8 is a bottom plan view thereof.

The broken line showing of various surface features is included for the purpose of illustrating portions of the front weight for an agricultural tractor and forms no part of the claimed design.

1 Claim, 8 Drawing Sheets**FIG. 1**

FIG. 2

FIG. 3

FIG. 4

FIG. 5

FIG. 6

FIG. 7

FIG. 8
